PARENTERAL INJECTION DEVICE

John E. B. Shaw, Chicago, Ill.

Application August 26, 1942, Serial No. 456,454

2 Claims. (CL 215—37)

My invention relates to a container having a solution for a parenteral injection, and to a stopper and seal for the container.

Heretofore it has been customary to provide a rubber plug for parenteral injection bottles which had to be pierced or fractured. This has resulted in ruining the plug so that it cannot be used more than once. During times of war or other periods of scarcity of materials, this results in great waste. It is among the objects of my invention to provide a plug that does not have to be pierced or fractured, and which may be used many times after appropriate cleaning and sterilization. This is an invaluable saving of rubber.

Another object is to provide a construction assuring a more positive seal, and without the need of metal or rubber washers and other extraneous parts.

My invention contemplates such further objects, advantages and capabilities as will later more fully appear and which are inherently possessed by my invention.

While I have shown in the accompanying drawing a preferred form of my invention, yet I wish it understood that the same is susceptible of modification and change without departing from the spirit of my invention.

Referring to the drawing, Fig. 1 is a side elevational view of a parenteral injection bottle; Fig. 2 is a top plan view of my stopper; Fig. 3 is a detailed sectional view of my stopper on the bottle with the cap in closed position; Fig. 4 is a detailed sectional view with the cap removed showing the opening of my stopper and Fig. 5 is a detailed sectional view of my stopper in open position on the bottle ready for use.

The embodiment selected to illustrate my invention comprises a container 10 containing a sterile solution for parenteral injections, such as dextrose, glucose, sodium chloride or the like. Within the neck 11 of container 10 the lower portion 12 of a plug or stopper 13, preferably made of rubber, composition or the like, is positioned by friction grip. Spaced openings 14 and 15 extend vertically through the lower portion 12 of said plug 13, and in opening 14 is positioned the upper end of hollow air tube 16 of glass or other suitable material. The tube 16 extends downwardly within container 10, with its lower end above the bottom of the container.

Said stopper 13 has a flange 17 which rests on the top 35 of container 10. Said stopper 13 also has an upper portion 18 with a passage 19 therein positioned to communicate with liquid flow open-

ing 15, when said upper portion is in normal upstanding position.

Within said passage 19 of upper portion 18 of plug 13 and attached to or integral with the inner wall 20 thereof is a nub 21. Said nub has an inwardly converging portion 22 and an outwardly diverging end portion 23.

Integral with or attached to the opposite outer wall 24 of upper portion 18 of plug 13 is a protuberance 25 having an inwardly converging portion 26 and an outwardly diverging end portion 27.

In the laboratory after container 10 has received the desired liquid, plug 13 is positioned 15 with its lower portion 12 within the neck 11 and flange 17 over the top 35 of container 10. Air inlet tube 16 is positioned with its upper portion in opening 14 in plug 13. The upper portion 18 of plug 13 is moved diagonally downwardly until nub 21 is within liquid flow opening 15, and protuberance 25 is within air supply opening 14. Openings 14 and 15 each have inwardly inclined portions 28 adapted to receive and to permit entry of said nub 21 and protuberance 25, and adapted to snugly engage their respective enlarged end portions 23 and 27 and prevent accidental displacement.

In the above described sealed position, the upper portion 18 of plug 13 extends substantially 30 in a horizontal plane. A closure 29 has a downwardly extending peripheral flange 30 with screw threads 31 to engage the screw threads 32 on the outer portion of the neck 11 of the container 10. This retains the plug 12 in place to form a perfect seal.

When the container is to be used for a parenteral injection, the hospital attendant removes the closure 29 and applies upward pressure to the upper portion 18 of the plug adjacent its mouth 33 as shown in Fig. 4. This moves protuberance 25 out of air inlet opening 14 and nub 21 away from liquid flow opening 15. Upper portion 18 of plug 13 then resumes a substantially vertical position. To the mouth 33 a tube with a sterile needle at 45 the other end (not shown) may be attached for the parenteral injection.

Having thus described my invention, I claim:

1. In combination with a container having 50 sterile injection solution therein and a neck, a stopper having a lower portion positioned within and against the neck of the container, said lower portion having a liquid outlet opening and an air inlet opening therethrough, said stopper having an upper portion with a passage therethrough and communicating with said liquid outlet open-

ing in said lower portion in normal upstanding position, said upper portion having a nub extending within said passage, and a protuberance on its opposite outer wall, said upper portion adapted to be moved diagonally downwardly so that said nub is engaged within and seals said liquid outlet opening, and said protuberance is engaged within and seals said air inlet opening, and a removable closure for retaining said stopper in closed sealing position, said upper portion adapted upon removal of said closure, to be moved diagonally upwardly toward upstanding position so that said nub and said protuberance are removed from said openings, said upper portion having a mouth adapted to receive in upstanding position a tubing connected to an injection needle.

2. A stopper for a parenteral injection con-

5 tainer having a plug portion adapted to fit within the neck of said container by friction grip, said plug portion having a pair of spaced openings therethrough, said stopper having an upper portion extending above said plug portion, said upper portion having a pair of spaced knobs, said upper portion adapted to be moved diagonally downwardly so that said knobs engage within and seal said openings, said upper portion also 10 adapted to be moved diagonally upwardly so that said knobs are removed from said openings, said upper portion in upstanding position having a passage therein communicating with one of said openings, said upper portion having a mouth adapted to receive a tubing connected to an injection needle.

15 JOHN E. B. SHAW.
